ceased

Application April 1, 1942, Serial No. 437,140

6 Claims. (Cl. 250—20)

It is known that a frequency responsive electrical transmission network which provides full output response to a predetermined tone frequency of normal amplitude and which provides an output response of much lesser value for a frequency which differs from the predetermined tone frequency by a rather small amount as, for example, 10%, may be constructed by connecting a series of highly selective resonant circuits in cascade. Each of such highly selective resonant circuits ordinarily has a high ratio of inductance to resistance (high Q), this ratio having a value of the order of from 100 to 160 in the selective circuits of the usual radio receiver. Such a frequency selective network which is responsive to audio frequencies of the order of 5000 to 7000 cycles necessarily has bulky coils so that it takes up a large amount of space and runs into considerable weight and is expensive to construct. It is accordingly an object of the present invention to provide a frequency selective transmission network which is highly selective as to different frequencies yet is at the same time of small weight and size and inexpensive to construct.

It is known that such high Q circuits have a small decrement and it follows that a large number of voltage impulses of the resonant tone frequency must be applied before the current in the first circuit of the series is built up to its full value and an additional time must elapse before the current in the other circuits in succession reaches its maximum value. In certain applications speed of operation of a frequency selective network is of great importance and highly advantageous and it is one of the purposes of the present invention to provide a frequency selective network comprising one or a few resonant circuits in which the ratio of the inductance to the resistance has a low value, a value of the order of from 18 to 26 having been found suitable. Such circuits have a high decrement and conversely within a few cycles after the application of the resonant tone frequency thereto, the full output voltage is built up in the last circuit of the series. In the illustrated embodiment of the invention, in which a pair of coupled circuits are resonant to 7000 cycles and in which the ratio of the inductance to the resistance of each circuit has a value of approximately 20, only about 20 cycles of the energizing voltage has to be applied before the full output voltage is developed across the circuits. This corresponds to a time of 3 milliseconds and it will be understood that in other installations responsive to higher frequencies, the full response may be built up within a still shorter time inter-

val, due to the greater number of cycles in a given unit of time. In the illustrated embodiment of the invention, two resonant circuits connected in cascade are shown although it will be understood that in certain installations a single resonant circuit may be found to provide sufficient selectivity and in other installations where a still greater degree of selectivity is desired three or more such resonant circuits may be connected in cascade.

Any resonant device can be driven to any amplitude at any frequency by the application of sufficient power. It is an important feature of the present invention that the amount of power supplied to the resonant circuit or circuits is limited to a predetermined value which is insufficient to develop any output voltage across the output terminals of the frequency selective network for any applied frequency which differs from the resonant frequency by 10 per cent or more. For this purpose a limiter tube is used, the signal frequency being applied to its grid and its plate circuit being coupled to the resonant circuit to supply a limited amount of energy thereto. In the illustrated embodiment of the invention, this energy is sufficient for a signal of the resonant frequency and normal strength to develop a peak output voltage across the resonant circuit of approximately 20 volts. However, for a signal frequency which differs from the resonant frequency by 10 per cent, the energy supplied by the limiter tube for a signal of maximum possible strength is only sufficient to develop a voltage of substantially 9 volts across the resonant circuit.

It is a further object of the invention to prevent such a voltage generated by an undesired frequency from causing any output voltage whatsoever to appear across the output terminals of the frequency selective network.

This is secured by providing as part of the frequency selective network a device associated with the resonant circuit or circuits which is non-responsive to input voltages below a predetermined level. This device is so arranged that for any usable input voltage of the resonant frequency a substantial direct current output voltage is developed across the output terminals of the transmission network while for an input voltage of any magnitude, no matter how large, having a frequency differing from the resonant frequency by substantially 10%, no output voltage whatever is developed across output terminals of the network. Stated in other terms, the ratio between the output voltage for the desired frequency and that for an undesired fre-

quency is infinitely large, corresponding to an infinite degree of selectivity.

If a very large transient voltage were applied to the resonant circuits of a frequency selective network, the resonant circuit or circuits thereof may be caused to oscillate at their resonant frequency by shock excitation and generate a substantial voltage across the output terminals of the network.

In applicant's co-pending application Serial No. 321,378, filed February 29, 1940, now Patent No. 2,283,523, dated May 19, 1942, of which this application is a continuation in part, the frequency selective network is shown as forming part of a radio receiver which automatically scans the frequency spectrum and locks on a received carrier modulated by the tone frequency to which the frequency selective network is responsive. The invention however is not limited to such use but has a wide field of application and is adapted for use in any electrical system in which different devices are provided each designed to be operated by a different tone frequency such, for example, as multiplex facsimile, teletype and telegraph systems.

For a better understanding of the invention reference is made to the following description taken in connection with the accompanying drawings, in which:

Fig. 1 is a schematic circuit diagram of an electrical transmission network embodying the invention;

Fig. 2 shows the response curves across one of the circuits of Fig. 1 for different applied frequencies;

Fig. 3 is a sectional view showing the construction of a transformer unit embodying the invention; and

Figs. 4 and 5 are schematic views illustrating certain mechanical arrangements explanatory of the operation of the invention.

Referring to Fig. 1, the invention is shown as comprising a limiter tube VT7 to whose grid a source of voltage 10 of variable tone frequency is connected, the usual grid biasing resistor 11 being connected in the cathode circuit and the plate of the tube being resistance coupled to the resonant circuit TC3 by the resistor R17 and condenser C7. The circuit TC3 comprises the primary transformer winding or coil 12 and a trimmer condenser 13 which is adjustable to tune the circuit to the desired tone frequency, which may be in the sub-audio, audio or super-audio range of frequencies. The coil 12 is optimum coupled to the secondary winding 14 of the resonant circuit TC4 so as to transfer the maximum energy to this circuit at the resonant frequency. A trimmer condenser 15 is provided for tuning the circuit TC4 to the tone frequency. In order to greatly increase the inductance of the resonant circuits, each of the coils 12 and 14 is provided with a compressed powdered iron core 16 and 17, the size of the iron particles which compose these cores being suitable for the operating frequency. The lower terminal of the circuit TC4 is connected to the cathode 19 of the diode rectifier tube VT9 through the load resistor R11 and a 10 volt bias battery 20 while the upper terminal of the circuit is connected to the plate 18 of the diode. The rectified voltage developed across R11 is filtered by the filter circuit comprising resistor R12 and condenser C8 and appears across the output terminals 21 of the transmission network as a direct current voltage Eo.

Referring to Fig. 2, the full line curve A indicates the peak volts developed across the resonant circuit TC4 for different tone frequencies of the normal amplitude of 5 volts generated by

5 the source 10, the circuits TC3 and TC4 being resonant at 7 kc. At this frequency it will be observed that a maximum peak voltage of 20 volts is developed across the circuit TC4, but since the diode VT9 has an initial negative bias 10 voltage of -10 volts, the useful net output voltage Eo appearing across the terminals 21 has a value of 10 volts, as indicated on the scale at the right of Fig. 2. It will also be observed that at frequencies of 6 kc. and 8 kc. only about 2 volts 15 is developed across the circuit TC4, which is insufficient to overcome the 10 volts negative bias of the diode VT9 and therefore produces no output voltage Eo whatsoever across the output terminals 21. The curve B in dash lines shows the 20 peak voltage across the resonant circuit TC4 when the maximum strength of signal is applied to the grid of tube VT7 and when the current in its plate circuit has been fully modulated and beyond which no further increase in the power 25 delivered by the plate circuit is possible by reason of the limiting action of the tube. In the illustrated embodiment of the invention, it is found that beyond a voltage of 15 volts applied to the grid of the limiter tube VT7 no further increase 30 in modulation of its plate current takes place so that the power supplied to the resonant primary circuit TC3 is definitely limited to a predetermined maximum value. From curve B it will be observed that for frequencies of 6 kc. and 8 kc. 35 only about 6 volts is developed across the circuit TC4 which, of course, is insufficient to overcome the 10 volts bias of the diode and develop any output voltage Eo across the output terminals 21 of the transmission network. From an inspection 40 of curve B it will also be observed that for applied frequencies which differ from the resonant frequency of 7 kc. by more than approximately 650 cycles, no direct current output voltage is developed across the output terminals 21, 45 so that as between such frequencies and the resonant frequency, the transmission network has infinite selectivity.

If current were supplied to the circuit TC3 from a source which was capable of supplying a 50 large amount of power or energy thereto, it would be possible for large transient voltages of steep slope to energize the resonant circuits TC3—TC4 by shock excitation and thus cause them to oscillate at full amplitude at the frequency of 7 kc. This action would cause an output voltage Eo to appear, even in the absence of the tone frequency to which the network is normally responsive. This action is prevented, however, by the use of the limiter tube VT7 whose 55 plate circuit delivers insufficient power to the circuit TC3 in response to the impression on its grid of an abrupt transient voltage of any amplitude to cause this circuit to oscillate strongly at its resonant frequency and thus generate an 60 output voltage Eo across the terminals 21.

A feature of the invention is the construction of the resonant circuits TC3 and TC4 in such a manner that they have a high decrement and become fully excited within a very short time 65 after the application of the resonant frequency voltage thereto. For this purpose the coils of these circuits are designed to provide a low ratio of inductance to resistance (Q), as, for example, a ratio of the order of from 18 to 26 and in the 70 illustrated embodiment of the invention, a Q of 75

20 was found suitable. With such low Q coils, it is feasible to develop the full output voltage at the terminals of the transmission network within 3 milliseconds after the application of the tone frequency to its input terminals. This rapidity of response is highly important in certain applications of frequency selective networks and it will be understood that by using circuits having a somewhat lower Q, the full output response may be developed within a still shorter time interval at the same frequency after the application of the energizing voltage.

The action of the limiting tube VT1 and the biased diode VT9 in connection with the resonant circuits may be understood more clearly upon consideration of the analogous mechanical systems schematically shown in Figs. 4 and 5. In Fig. 4 a pendulum 22 is shown supported for free oscillation within a closed casing 23 provided at one end with an opening 24. A small weight 25 is suspended on a string 26 so as to extend into the opening 24 and to strike against the bob 27 of the pendulum 22 when struck lightly by a hammer 28. By making the bob 27 relatively small and of a light metal, such as aluminum, the pendulum 22 will have a large decrement. Also by striking the weight 25 by the hammer 28 repeatedly at the natural period of vibration of the pendulum 22, the pendulum will be set into oscillation at its natural period and only a small number of energy impulses as, for example, 20 by the weight 25, will be required to cause the pendulum to oscillate through its full range of movement. The bob 27 is adapted to engage a switch lever 29 which is normally biased against a stationary stop 30 by a spring 31, so that as soon as the swing of pendulum 22 reaches its full amplitude the switch 29 is closed establishing the flow of current through a local circuit including a battery 32 and bell 33. The pendulum 22 of small mass and high damping corresponds to the low Q circuits TC3-TC4 in that only a small number of energizing impulses at the proper frequency are required to cause the pendulum to vibrate fully at its natural period, which in turn causes the bell 33 to respond.

In the arrangement of Fig. 5, the pendulum 34 is not enclosed and while it is of the same length and has the same natural period as the pendulum 22, yet its bob 35 is made of lead or other heavy metal and has a mass many times that of the bob 27. This pendulum has a very much lesser damping and decrement than the pendulum 22 and corresponds to a high Q circuit in that it must be struck a large number as, for example, 200 blows at its natural period by the small hammer 28' before it will oscillate at its full amplitude and thus close the switch 29' and cause the operation of the bell 33'. A high Q circuit, having a small damping and decrement, requires the application thereto of a large number of small voltage impulses of its resonant frequency before it becomes fully excited. Should, however, the bob 35 be struck a single hard blow by a massive hammer, which would correspond to the full excitation of the circuit TC3 by a large transient voltage, the pendulum 34 will at once be set into full oscillation at its natural period and immediately close the switch 29' and cause the operation of the bell 33'. This impulse excitation of the pendulum 22 by the hammer 28 is prevented however by reason of the interposition between the hammer and the bob 27 of a weight 25 of such small mass that it possesses insufficient energy

to move the bob any substantial distance by a single blow even if the weight 25 is struck hard by a large hammer. The arrangement of Fig. 4 thus permits the bell 33 to respond rather quickly to small impulses of the proper frequency applied to weight 25 while at the same time causing no operation of the bell in response to a single shock impulse of the weight 25, however, large. The function performed by the weight 25 corresponds to that performed in the circuit arrangement of Fig. 1 by the limiter tube VT1, the plate circuit of this tube supplying insufficient energy to the resonant circuit TC3 to build up sufficient current in this circuit to cause any output voltage whatever to be developed across the terminals 21 even in response to the impression of a large transient voltage on the grid circuit of tube VT1. The circuit arrangement is thus seen to be quickly responsive to the desired tone frequency and to be entirely non-responsive to frequencies which differ therefrom by 10% or more and also to large transient voltages.

It will be understood that any other known type of electrically operated device which requires the application of a voltage above a predetermined minimum value before it becomes energized may be substituted in place of the biased diode VT9 as, for example, certain types of thyratron tubes or a triode detector having its grid biased beyond cut-off.

A preferred mechanical arrangement of the circuits TC3-TC4 is shown in Fig. 3 in which a rectangular supporting base 36 of "Bakelite" is provided with a central aperture 37 and 5 projecting prongs 38 (only two being shown) adapted to be plugged into a socket. A pair of vertical brass supporting strips 39 have their lower ends bent over and secured to the base 36 by screws 40, a shelf 41 being secured to the upper end of the strips 39 by the screws 42. A lower shelf 43 is supported on a pair of small brass brackets 44 which are secured to the supporting strips 39 by screws 45. A pair of U-shaped brass brackets 46 are secured to the strips 39 by screws 47, these brackets supporting a pair of spaced apart shelves 48, 49 which are secured thereto by screws 50-51. The coil supporting shelves 41, 43, 48 and 49 are formed of suitable insulation material such as "Bakelite." The coil 12 with its powdered iron core 16 is held in position by being squeezed between the shelves 43 and 49 while the secondary coil 14 with its powdered iron core 17 is held coaxial with the coil 12 by being squeezed between the upper shelves 41-48. The trimmer condenser 13 for the coil 12 is affixed to the under side of shelf 43 and is provided with an adjusting screw 52 which may be operated by a screw-driver inserted through the opening 37 for the purpose of adjusting the capacity of the condenser to tune the circuit TC3 to the tone frequency. The trimmer condenser 15 for tuning the circuit TC4 to the tone frequency is secured to the upper shelf 41 and is provided with an adjusting screw 53. The component parts of the resonant circuits are enclosed in a rectangular shaped metallic shield can 54 which is provided at its top with an opening 55 through which the screw 53 projects slightly. The coils 12 and 14 are of layer wound copper wire with paper insulation between the layers and each coil is approximately 1 inch long and of $\frac{1}{8}$ inch diameter, the diameter of the iron cores being approximately $\frac{3}{8}$ inch. The size of the aluminum shield can 54 is $1\frac{1}{2} \times 2 \times 4$

inches and the weight of the entire plug-in assembly is only 4 ounces. By means of the construction described, a number of plug-in units may be provided, each tuned to a different tone frequency so that the transmission network may be quickly made responsive to any tone frequency by plugging in a unit resonant to that frequency.

The plug-in construction described provides a ready means for assembling and supporting low Q coils and for securing optimum coupling between the primary and secondary windings. As shown in the curves of Fig. 2, this arrangement has response curves which are relatively broad at their upper portions.

In a transmission network responsive to a frequency of 7000 cycles, the following circuit constants were found suitable.

$C_7=250$ mmf. $R_{17}=125,000$ ohms
 $C_8=150$ mmf. $R_{11}=100,000$ ohms
 $R_{12}=50,000$ ohms

Inductance of coils 12 and 14 from 130 mh. to 200 mh.

Q of coils 12 and 14 from 26 mh. to 18 mh.

Vacuum tubes of the following types are found suitable for use with the circuits described.

VT7=one section of a 6N7 double triode

VT9=double diode triode, 6R7

I have described what I believe to be the best 30 embodiments of my invention. I do not wish, however, to be confined to the embodiments shown, but what I desire to cover by Letters Patent is set forth in the appended claims.

I claim:

1. A frequency selective transmission network comprising, in combination, a limiter tube, a resonant circuit having a low ratio of reactance to resistance and a detecting device connected in cascade and including parts which are unresponsively related below a predetermined threshold value of applied voltage, said parts having interacting and responsive relationship above said threshold value of applied voltage, whereby the ratio between the selectivity and the number of cycles required to build up to full amplitude in the output of said transmission network is markedly increased over the ratio inherent in any resonant circuit alone.

2. A frequency selective transmission network comprising, in combination, at least one circuit resonant to a predetermined tone frequency, a limiter tube arranged to impress voltages of a range of frequencies including said tone frequency on said resonant circuit, a detecting device including parts which are unresponsively related below a predetermined threshold value of applied voltage, said parts having interacting and responsive relationship above said threshold value of applied voltage, a circuit connecting said detecting device to said resonant circuit, and a load impedance in the output circuit of said detecting device, said threshold voltage having such a value that upon the impression of a voltage of said tone frequency in excess of a predetermined minimum value on the input circuit of the limiter tube a direct current voltage of substantial amount is developed across said load impedance but upon the impression on the input circuit of the tube of a voltage of any magnitude having a frequency differing by at least 10 per cent from said tone frequency, no voltage is developed across said load impedance.

3. A frequency selective transmission network comprising, in combination, at least one circuit

resonant to a predetermined tone frequency, a limiter tube arranged to impress voltages of a range of frequencies including said tone frequency on said circuit, a detecting device, and a circuit comprising a source of steady bias voltage and a load impedance connecting the terminals of the detecting device to said resonant circuit, said source of bias voltage having such a value that upon the impression of a voltage of said tone frequency in excess of a predetermined minimum value on the input circuit of the limiter tube, a voltage of substantial value is developed across said load impedance but upon the impression on the input circuit of the limiter tube of a voltage of any magnitude having a frequency differing by at least 10 per cent from said tone frequency, no voltage is developed across said load impedance.

4. A frequency selective transmission network 20 comprising, in combination, at least one circuit resonant to a predetermined tone frequency, a limiter tube arranged to impress voltages of a range of frequencies including said tone frequency on said resonant circuit, a detecting device connected in cascade and including parts which are unresponsively related below a predetermined minimum threshold value of applied voltage, said parts having interacting and responsive relationship above said threshold value of applied voltage, said device coupled to said resonant circuit and a load impedance in the output circuit of said detecting device, said threshold voltage having such a value that upon the impression of a voltage of any amplitude having a frequency differing by at least 10 per cent from said tone frequency no voltage is developed across said load impedance but upon the impression of a small number of cycles of a voltage of said tone frequency in excess of a predetermined minimum value on the input circuit of the limiter tube, a direct voltage of substantial amount is developed across said load impedance.

5. A frequency selective transmission network comprising, in combination, at least one circuit resonant to a predetermined tone frequency, a limiter tube arranged to impress voltages of a range of frequencies including said tone frequency on said resonant circuit, a detecting device connected in cascade and including parts which are unresponsively related below a predetermined minimum threshold value of applied voltage, said parts having interacting and responsive relationship above said threshold value of applied voltage coupled to said resonant circuit, and a load impedance in the output circuit of said detecting device, said threshold voltage having such a value that upon the impression of a voltage of said tone frequency in excess of a predetermined minimum value on the input circuit of the limiter tube a direct current voltage of substantial amount is developed across said load impedance but upon the impression of a single transient pulse of any voltage or slope on the input circuit of the tube, no voltage is developed across said load impedance.

6. A frequency selective transmission network comprising, in combination, a driver tube having an output circuit, a detecting device having a load circuit including a source of steady bias voltage, and at least one circuit resonant to a predetermined tone frequency and arranged to couple the output circuit of said driver tube to said detecting device, said resonant circuit being so designed that the ratio of the reactance to the resistance thereof has such a low value that upon the excita-

tion of the resonant circuit by current of the tone frequency in the output circuit of the driver tube, the current in the resonant circuit builds up to maximum value within a few cycles thereby generating in the load circuit of the detecting device a voltage which is greater than that of the bias voltage source and causing a direct current to flow in said load circuit, the constants

of said driver tube and its output circuit being so selected that for a current therein of a frequency only slightly different than said tone frequency, the voltage built up in the resonant circuit is insufficient to generate a current in the load circuit of the detector.

SIDNEY Y. WHITE.
